UNITED STATES PATENT OFFICE.

JOHN LOVEJOY, OF WEST LEBANON, NEW HAMPSHIRE.

RAILWAY SWITCH-ROD AND RAIL-COUPLER.

SPECIFICATION forming part of Letters Patent No. 269,529, dated December 26, 1882.

Application filed October 3, 1882. (No model.)

To all whom it may concern:

Be it known that I, JOHN LOVEJOY, a citizen of the United States, residing at West Lebanon, in the county of Grafton and State of New Hampshire, have invented certain new and useful Improvements in Railway Switch-Rods and Rail-Couplers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The ordinary switch-rod consists of a straight wrought-iron bar having lips turned over at each end to clasp the outside of the rail. A lip is also welded to the rod on the inside of each rail at a point just far enough from the 20 end lips to inclose the flanges of each rail. This necessitates the slipping of the lips over the flanges at the end of the rail and driving it along the length of each rail to its place. There being five or six rods to each switch, those 25 nearest the center cannot afterward be removed without also removing all the others between it and the end of the rail. The constant use of switches, and the extra strain resulting from their not being attached to sleepers, like 30 the ordinary rails, is likely to cause the breaking of the rods, or, what is more frequently the case, the bending of the rods and displacement of the lips, resulting in a derangement of the gage, for which there is no remedy except in 35 removing the rod, straightening and rewelding the lips to take up the slack.

The object of my invention is to obviate these faults and to furnish a means for securely coupling the rails and preserving the gage, 40 both simple and effective; also, to provide means of allowing any one of the switch-rods to be removed without interfering with the others; also, to provide a way of taking up any slack resulting from constant jarring without 45 removing the rod at all.

Figure 1 is a side view of one end of my switch-rod and coupler, showing the application of my device for connecting switch-rails. Fig. 2 is a vertical longitudinal section of the

other end. Fig. 3 is a plan view of one end of my device.

Like letters refer to like parts.

The switch-rod B consists of a bar or rod of iron or steel of suitable size. At each end, at proper distances to secure the outside flange 55 of the rail A, a lip, a, is turned up. The rod B is cut away or grooved near each end for passing under or receiving the rail. (See b, Fig. 2.) The inner wall of this groove slopes backward at a point, b', near the top, in order 60 that the rail may be easily inserted in said groove and under the outer clutch or removed.

The collars C C are of iron or steel, recessed across their faces to make lips c to slide over the inner flange of the rail sufficiently to securely fasten the rails to the rod.

Through each collar is a hole of suitable size to make said collar fit the rod closely and allow the former to be moved in either direction. A slot, d, is cut through the rod, at a proper distance in the rear of the collars, for the reception of a wedge-key, D, so as to allow tightening when required. Holes h are made at proper distances in the smaller end of the keys for inserting wedge-pins p, padlocks, or any other sufficient fastening for securing the key and preventing slack.

The same arrangement above described can be used for connecting the switch with the switch-frame by using a similar rod fitted with 80 the lip and collar to fasten to the end of the rail next to the switch-frame, the other end of the rod being left plain, but of sufficient length to make the connection at the switch-frame. The switch-rod in direct contact with the rails 85 is especially desirable, as it requires no ditching or other preparation of the ground, makes a stronger connection than can be obtained by the intervention of any substance between the rail and switch-rod, and is easily freed from 90 ice and snow in winter.

If the rails require to be removed for any purpose, the keys can be easily taken out, the collars slipped toward the center of the rod, and new rails inserted with as much facility as upon 95 any part of the track.

It will be seen that my device is simple, effective, and cheaply made.

What I claim, and desire to secure by Letters Patent, is—

1. A switch-rod slotted to form a solid clutch for the outer flange of the rail, and having the inner wall of said slot vertical, except where cut away near the top, as shown, to give the rail a firm bed and allow it to be easily inserted and removed, substantially as set forth.

2. The combination, with the switch-rails, of the slotted switch-rod having wedge-keys and sliding collars, substantially as set forth.

In testimony whereof I affix my signature in presence of two witnesses.

JOHN LOVEJOY.
